UNITED STATES PATENT OFFICE.

WILLIAM F. DEVAN, OF GWIN MINE, CALIFORNIA.

APPARATUS FOR SEPARATING SULPHURETS IN ORE-WASHING.

SPECIFICATION forming part of Letters Patent No. 242,610, dated June 7, 1881.

Application filed July 14, 1880. (No model.)

To all whom it may concern:

Be it known that I, WILLIAM F. DEVAN, of Gwin Mine, Calaveras county, California, have invented a new and useful Improvement in 5 Apparatus for Separating Sulphurets in Ore-Washing, of which the following is a specification.

The object of my invention is to improve ore-washers and save the sulphurets by an operation that is both continuous and economical, as hereinafter described.

In the accompanying drawings, Figure 1 is a plan view of my improved apparatus. Fig. 2 is a vertical longitudinal section of the same. Fig. 3 is a vertical transverse section on line *x x*, Fig. 1; and Fig. 4 is a similar view on line *y y*.

Similar letters of reference indicate corresponding parts.

20 A *A* are tanks fitted above the sluices *B*, and provided with gates *a*, whereby their contents may be discharged into the sluices, as desired.

b b' are boxes fitted above each tank *A*, for containing and supplying water to the tanks 25 by the gates *e* in boxes *b*, or pipes *c'* from boxes *b'*.

d d are similar water-boxes resting on the sluices *B*, for supplying water thereto.

e is the pulp-box, extending from one tank 30 *A* to the other, and fitted with gates *f f* above the tanks. The tanks *A* are provided at their ends with removable boards *g*, which may be taken out to give access to the tanks, and replaced when the tanks are to be filled.

35 *C C* are the boxes for saving the sulphurets. These are formed as continuations of the sluices *B*, and are fitted with riffles *h* at suitable distances apart.

i is a drainage-trough fitted at the under 40 side of boxes *C* and communicating therewith by openings *k*.

In operation the pulp from the stamp-mills is led to the pulp-box *e*, and by opening one of the gates *f* the pulp enters one tank *A*. The 45 gate *c* of the water-box *b* is then to be opened, and the end boards, *g*, of the tank put in place as the tank fills with pulp.

It will be seen that during the filling any 50 amount of water required for the washing can be supplied. The tank *A* being filled, the gate *f*, opened to discharge the pulp to the other

tank, in which the washing will be carried on, as described. The separation of the sulphurets from the pulp in the tank first filled proceeds 55 at the same time. The gates *a* are hoisted to run the contents of the tank into the sluices *B* and boxes *C*, water being at the same time admitted from box *b'* by the pipes *c'*, which discharge close to the gates *a*, so that the pulp 60 is carried out freely. At the same time water is admitted to the sluices *B* from boxes *d*, to carry the pulp into boxes *C*, where the final washing and separation is done. The sand and sulphurets will settle and be retained in 65 the bottoms of the boxes *C*, while the water passes out at the ends of the boxes. After the boxes *C* have drained out by the trough *i* the sand and sulphurets are to be taken out and washed in a baffle. The collections of 70 low-grade ore may be dumped into the head of the sluices *B*, for working with the pulp at the next washing, and the refuse from the baffle may also be worked over in the same manner.

By this apparatus but a small percentage of 75 the sulphurets need be lost.

The boxes *C* may be extended to any length required for proper separation.

These works may be constructed comparatively cheap.

80 By the use of the tanks, constructed as described, the useless sediment is first removed without loss of sulphurets, and the subsequent separation rendered easier. The separate tanks allow continuous work of separation without 85 interrupting the flow of pulp from the mill.

Having thus described my invention, I claim as new and desire to secure by Letters Patent—

1. The apparatus for washing ores for the 90 separation and saving of the sulphurets, consisting of pulp-tanks *A*, provided with discharge-gates *a*, removable boards *g*, and water-supply boxes *b b'*, combined with the sluices *B* and washing-boxes *C*, for operation as specified.

2. The boxes *C*, provided with riffles *h* and water-boxes *d*, combined with the pulp-tanks *A* and sluices *B*, substantially as and for the purposes set forth.

WITNESSES:

CHARLES B. HIGBY,
WESLEY K. BOUCHER.
